UNITED STATES PATENT OFFICE.

PETER GRAHAM MACGREGOR, OF NEW YORK, N. Y., ASSIGNOR TO PETER G. MACGREGOR,
EDWARD M. DAVIDSON, AND PETER L. WILBUR.

CONTACT-OILER.

1,127,367.

Specification of Letters Patent.

Patented Feb. 2, 1915.

Application filed December 13, 1912. Serial No. 736,645. Renewed April 30, 1914. Serial No. 835,545.

To all whom it may concern:

Be it known that I, PETER G. MACGREGOR, a citizen of the United States, and resident of the city, county, and State of New York, have invented certain new and useful Improvements in Contact-Oilers, of which the following is a specification.

This invention relates to a device for oiling the contact members of an electric circuit closing device.

The object of the invention is to provide a device or an attachment especially adapted for use with street car controllers for reducing the wear and friction between the contact members.

The object of the invention is to provide a simple and efficient device for the purpose specified which may be readily attached to any circuit closing device or controller of standard construction.

In the drawings like parts of the several views have been given the same reference numeral.

Figure 1 is a sectional plan view of a portion of a controller showing the oiling device attached thereto. Fig. 2 is an enlarged sectional plan view of the device. Fig. 3 is an enlarged sectional side elevation of a portion of Fig. 1.

The base of the controller is shown at 1 and the cover at 2. The contacts 3, 4 and 5 are rotatively mounted upon the shaft 6 and operated in the usual manner by means of a hand crank or lever, not shown. The contact finger 7 is carried by a resilient member 8 mounted upon a suitable support 9 attached to the base 1. These parts may be of any standard construction for a device of this nature and no novelty is claimed for these features. The contacts are partially inclosed by a cover 10 of insulating material which may be provided with barriers extending between the different series of contacts.

The oiling device consists of a number of blocks of absorbent material, such as felt, shown at 11, 12, and 13. It will be understood that a number of these blocks of absorbent material are provided to correspond to the number of series of contacts. Each of these blocks of absorbent material is positioned in and projects through openings in the cover 10 and are positioned over the several

contacts so that the inner face of the block projects slightly beyond the path of the outer surface of the contacts.

A tubular member 14 extends through the series of absorbent blocks 11, 12 and 13 and is held in a retaining member 15, which is in the form of a channel in which the outer ends of the blocks 11, 12 and 13 are held. This provides for the removal of the oiling device as a unit. The upper end of the retaining member 15 is preferably funnel shaped, as shown at 16, and communicates with the tubular member 14, providing a convenient means of supplying the oil or other lubricating material to the absorbent blocks 11, 12 and 13.

A series of openings, such as 17, 18 and 19, are provided in the tubular member 14 at the point where the same passes through the absorbent blocks 11, 12 and 13. These openings decrease in size from the upper opening to the lower so that when the oil is poured into the receptacle 16, filling the tubular member 14, the same will be supplied and absorbed by the blocks. As the oil is absorbed the level of the same in the tubular member 14 falls and, consequently, if the openings were all of the same size, the lower block 13 would receive more oil than the upper block 11 and either the upper block would not be sufficiently saturated or the lower block would receive an excess amount. To insure each of the blocks being supplied with a proper amount of oil the openings decrease in size, as above described, thus supplying more oil to the upper block during the shorter period of time that the level of the oil is high enough to supply this block and decreasing the size of the openings for each succeeding block, inversely in proportion to the time during which the oil is supplied through said openings, so that each block is supplied with and absorbs substantially the same amount.

The forward edges of the blocks 11, 12 and 13 are beveled or formed at an angle so that when the same are engaged by the rotation of the contacts 3, 4 and 5, the blocks are at first slightly compressed, thus forcing a portion of the oil or lubricating material with which it is saturated to the outer surface, from which it is then distributed over the face of the contact by the further move-

ment thereof. It will be understood that any number of these blocks may be provided, one for each series of contacts.

What I claim is:

5. 1. In a device of the class described, the combination with a series of movable contacts, of a series of absorbent members each positioned to engage one of said contacts, and means for supplying a uniform amount 10 of oil to said absorbent members.
2. In a device of the class described, the combination with a series of movable contacts, of a series of absorbent members each positioned to engage one of said contacts, 15 and means for supplying a uniform amount of oil simultaneously to said absorbent members.
3. In a device of the class described, the combination with a series of movable contacts, of a series of absorbent members each positioned to engage one of said contacts, and a tubular member extending through 20 said absorbent members for supplying oil thereto.
4. In a device of the class described, the combination with a series of movable contacts, of a series of absorbent members each positioned to engage one of said contacts, and a tubular member extending through 25 said absorbent members and provided with a series of openings for supplying oil thereto.

5. In a device of the class described, the combination with a series of movable contacts, of a series of absorbent members each 30 positioned to engage one of said contacts, and a tubular member extending from one to the other of said absorbent members and provided with a series of different size openings for supplying oil thereto.

6. In a device of the class described, the combination with a series of movable contacts, of a series of absorbent members each 35 positioned to engage one of said contacts, and a vertical tubular member provided 40 with a series of openings varying in size from the top to the bottom each adapted to supply oil to one of said absorbent members.

7. In a device of the class described, the combination with a series of movable contacts, of a series of absorbent members each 45 positioned to engage one of said contacts, and a vertical tubular member provided with a series of openings decreasing in size from the top to the bottom each adapted to 50 supply oil to one of said absorbent members.

Signed at New York city, in the county and State of New York, this 12th day of November, 1912.

PETER GRAHAM MACGREGOR.
